UNITED STATES PATENT OFFICE.

HEINRICH KNECHT, OF NEUHAUSEN, SWITZERLAND, ASSIGNOR TO THE FIRM SCHWEIZERISCHE INDUSTRIE GESELLSCHAFT, OF NEUHAUSEN, SWITZERLAND.

STARTING DEVICE FOR MOTOR-DRIVEN VEHICLES.

Application filed December 10, 1920. Serial No. 429,739.

To all whom it may concern:

Be it known that I, HEINRICH KNECHT, a citizen of the Republic of Switzerland, residing at Neuhausen, Schaffhauserstrasse 5 675, Switzerland, have invented certain new and useful Improvements in Starting Devices for Motor-Driven Vehicles; and I do hereby declare the following to be a clear, full, and exact description of the invention, 10 such as will enable others skilled in the art to which it appertains to make and use the same, reference being had to the accompanying drawing, and to letters or figures of reference marked thereon, which 15 form a part of this specification.

The invention relates to improvements in starting devices for motor driven vehicles and especially for motors which must start with no-load or with a small initial load and 20 with which the load can only be thrown on at higher speeds, as for instance is the case with internal combustion engines.

According to the invention the starting device comprises means to generate a pressure liquid and means driven by said pressure liquid which means can be interposed between the motor and the driving mechanism of a vehicle so that the motor drives the means generating the pressure liquid 30 and the second mentioned means are coupled to the driving mechanism, whereby the shocks occurring when starting the vehicle are absorbed by the liquid and a smooth start of the vehicle is attained.

An exemplification of the invention is 35 diagrammatically shown on the accompanying drawing in which:

Fig. 1 is a vertical longitudinal section of a vehicle fitted with the starting device, 40 Fig. 2 shows the starting device fitted to an elevator drive.

1 denotes an internal combustion engine on the shaft of which a fly-wheel 2 and a pinion 3 of a reduction gear 3^a are mounted. 45 The shaft 4 to which the other wheel of the reduction spur-gear 3^a is fixed is connected by means of a coupling 5 to a shaft 6 of a change speed gear 7, the latter being connected by means of shaft 8 and bevel gear 50 9 to the driving wheels 10.

The motor shaft is operatively connected to a pump 12 through the interposition of a friction coupling, one part of which is formed by the fly-wheel 2 and the other 55 part by a friction disc 11. The pump 12

delivers the liquid into a receiver 14, a pipe 15 fitted with a throttle valve 13 leads from the receiver 14 to a turbine 16. Spur gearing 17, 17^a and a coupling 18 is interposed between the turbine and the shaft 6. The 60 couplings or clutches 5 and 18 are operated by a hand lever *a* and suitable connecting elements.

In order to actuate the driving wheels 10 coupling 5 is thrown out and the couplings 65 2, 11 and 18 are thrown in, whereupon the motor is started up. Thereby the pump 12 is rotated and it draws the water discharged by the turbine and presses the water through the receiver 14 into the turbine 16. 70 The turbine actuated by the pressure water transmits the rotary motion through the spur gearing 17, 17^a and shaft 6 to the change gear 7 and from there to the driving wheels 10. After the latter are brought up 75 to speed the coupling 5 can be thrown in and the direct transmission of motion from the motor 1 through spur gearing 3^a, shaft 4 and shaft 6 of the change gear 7 to the driving wheels can be effected and the pump 80 12 as well as the turbine 16 can be cut out by disengaging the couplings 2, 11 and 18.

During the starting period the motive power of the motor acts upon the device producing the pressure liquid which in its 85 turn actuates the driving mechanism of the driving wheels, in consequence thereof the shocks resulting from the throwing in and out are absorbed by the liquid.

By means of the valve 13 the pressure of 90 the liquid and thereby the output of the motor can be throttled by degrees. The valve 13 permits the liquid to be gradually admitted to the turbines while the reservoir 14 contains sufficient liquid to compensate 95 for losses due to leakage from the system and also acts as a cooling device for the liquid. It will naturally contain air, and the quantity of air will vary in accordance with the leakage from the system.

This invention enables the avoidance of 100 the danger which exists with motors of larger outputs than the masses, to which a sudden acceleration has to be imparted when clutching in the motor, that might 105 cause a stoppage of the latter or a damaging of the transmission gear. In the starting gear according to the invention the motor actuates the means for generating a gradually increasing hydraulic pressure and the 110

pressure liquid actuates the driving mechanism to which a gradually increasing speed is imparted.

By means of the starting device described 5 above vehicles on an incline can be braked by throttling the liquid passage between the pump and the turbine. Such a device may also be used for actuating elevators as is 10 illustrated in Fig. 2. Motor, pump, turbine and the shafting are arranged in a similar manner to that shown in Fig 1 for driving a vehicle, with the exception that a rope drum 20 is fixed to shaft 8 and actuated by the latter, the rope 21 serving to hoist and 15 lower an elevator, which is not shown in the drawing. The energy of the descending elevator can be braked by throttling the liquid passage between pump and turbine.

I claim:

- 20 1. A starting device for motor driven vehicles, in combination, means for generating pressure on a liquid, and operatively connected to the motor, means actuated by said pressure liquid, a change speed gear interposed between the motor and the driving 25 wheels, and coupling means to cut out the operative connections between the motor and said means for generating pressure on the liquid and also between said means and the 30 means actuated by said pressure liquid after the motor has run up to its substantially normal speed and means to switch in the operative connections between the motor and the change speed gear.
- 35 2. A starting device for motor driven vehicles, in combination, means for generating pressure on a liquid, and operatively connected to the motor, means actuated by said pressure liquid, a change speed gear interposed between the motor and the driving 40 wheels, coupling means to cut out the operative connections between the motor and said means for generating pressure on the liquid and also between said means actuated

by said pressure liquid and said change speed gear after the motor has run up to its substantially normal speed and means to connect the motor and the change speed gear, and a throttling device interposed between said means for generating pressure liquid and said means actuated by said pressure liquid.

3. A starting device for motor-driven apparatus that has an engine driving a change speed mechanism, in combination with a coupling interposed between said engine and mechanism, a pump, a coupling between the pump and engine, a liquid motor driven by said pump and a disconnectable driving connection between said motor and mechanism. 60

4. A starting device for motor driven apparatus employing an engine and change speed mechanism, in combination with a clutch interposed between said engine and mechanism, a pump, a clutch between the pump and engine, a liquid motor driven by the liquid from said pump, means to deliver the discharge of said liquid motor to said pump, means to connect and disconnect said liquid motor from said mechanism and 70 means to control the flow of liquid through said liquid motor.

5. A starting device for motor driven apparatus employing an engine and change speed mechanism; in combination with 75 means to permit the connection and disconnection of said engine and mechanism, a pump driven by said engine, a clutch between them, a liquid receiver supplied with liquid by said pump, a liquid motor supplied 80 with liquid from said receiver, means to connect and disconnect said motor from said mechanism, means to connect the motor discharge to the pump inlet and means to throttle the liquid supply to said motor. 85

In testimony that I claim the foregoing as my invention, I have signed my name.

HEINRICH KNECHT.
